UNITED STATES PATENT OFFICE.

RALPH C. SIMMONS, OF BEVERLY, MASSACHUSETTS, ASSIGNOR TO UNITED SHOE MACHINERY COMPANY, OF PATERSON, NEW JERSEY, A CORPORATION OF NEW JERSEY.

HEEL-BREASTING MACHINE.

1,133,584.

Specification of Letters Patent.

Patented Mar. 30, 1915.

Application filed November 8, 1911. Serial No. 659,207.

To all whom it may concern:

Be it known that I, RALPH C. SIMMONS, a citizen of the United States, residing at Beverly, in the county of Essex and State 5 of Massachusetts, have invented certain Improvements in Heel-Breasting Machines, of which the following description, in connection with the accompanying drawings, is a specification, like reference characters on 10 the drawings indicating like parts in the several figures.

This invention relates to shoe machinery and is of particular utility when embodied in a machine for performing upon shoes 15 the operation of heel breeding, although I contemplate the use of my improvements for any purpose to which they are adapted.

An important feature of my invention is the provision of a machine of this class having 20 a plurality of power operated devices arranged to be presented respectively, for actuation at different times, to treat the work, which is preferably presented substantially in the same operating position, 25 regardless of the device selected for any given operation.

Another important feature of my invention 30 is the provision of positioning and clamping devices in a series corresponding to the aforesaid power operated devices, to serve respectively as guides and abutments, each preliminary to, and during, action by 35 the appropriate operating device, the series of operated devices being respectively movable, independently of each other, to their relative positions for coöperation upon the work.

A very important feature of my invention 40 is the provision of a series of breeding knives, and their appropriate abutment guides, so that they may be instantaneously presented in operative position by a simple turning movement, without preliminary adjustments, for breeding the heels of either 45 right or left shoes.

Another feature of importance is the provision, as part of the same series, of a breeding knife, and its corresponding abutment guide which has a contour differing 50 from others in the series.

Of similar importance also is the feature of my invention comprising means for effecting the substitution of a fresh knife for one which may have become worn, injured,

or out of adjustment, leaving the replacing 55 or readjusting of the knives thus disqualified to be effected at a time when the machine is at rest, or when it will not be disadvantageous to interfere with its operation.

A further feature of my invention is the provision of means for the successive treatment of the work by operating devices acting to perform their work progressively, as for example a simple curved breeding knife 65 succeeded by a scalloping knife, and the breeding device may be succeeded by the action of a member arranged to print the manufacturer's name or trade-mark upon a selected portion of the heel or shank. This 70 series of operating devices may be assembled in compact arrangement upon a turret, (which term I use as designating any rotatable support without further limitation,) and this turret may be adapted to existing 75 machines of this type. The abutment guides are preferably assembled in similar relation for their convenient adaptation to, and actuation in connection with, the co-operating parts of well-known heel breeding 80 machines.

Further means is provided also for the rapid adjustment of the aforesaid turrets by hand into their various positions, and means for locking them firmly at their several points of operation; also for swinging the turrets temporarily out of their operative planes to permit adjustive movements of the turrets themselves and to clear the work and operative parts of the machine for 90 access at times.

Accordingly, in carrying the invention into effect a support in the form of a turret is provided which is rotatable in a vertical plane and carries the operating devices. 95 For this purpose the turret is mounted upon a horizontal stud projecting from and reciprocable up and down with the front slide, for example, of a heel breeding machine, and I have devised a special form of 100 stop or bunter, one for each of the operating devices in the series, these serving interchangeably in coöperation with the means which disengages the usual connection pivoted at the rear of the front slide. 105 This connection is normally interposed between the knife slide and the rear or actuating slide which is connected with the pit-

man of the machine, so that when the pitman is reciprocated the breasting knife normally is operated to a point where further movement would cut the shank, and then 5 the bunter or stop touches the shank, knocks the strut out from under the roller on the rear slide, thereby disconnecting the knife slide from its actuating slide so that further downward movement of the pitman 10 and rear slide is not communicated to the breasting knife, but the latter is raised by the rear slide into position for another breasting stroke. By my improvements one strut and push rod serve for engagement 15 with a series of shipper levers mounted on the turret, one lever for, and coöoperating with, each of the breasting knives.

The various features of my invention will 20 be illustrated and described fully in the accompanying drawings and specification and pointed out in the claims.

In the drawings,—Figure 1 is a view in front elevation of a power heel breasting machine in the construction of which my 25 improvements have been embodied, parts being broken away to reveal more clearly the structure of other parts; Fig. 2 is a view in right side elevation of the head of said machine, on an enlarged scale; and Fig. 3 is a view in horizontal section on the line 3—3, 30 Fig. 1, looking in the direction of the arrows.

In the embodiment of my invention illustrated, the part designated by the reference 35 numeral 1 is the support for my improved mechanism, taking the form in the instance illustrated of a metal column, the lower part of which carries the usual power shaft 2 with fly wheel 3 connected intermittently by 40 a "Horton clutch" 4 which is controlled by a foot lever 5, serving to actuate intermittently a vertically reciprocating pitman 6 connected by a pin 7 with a rear slide 8 movable vertically in guideways formed in the frame. At 10 I have shown a front slide, 45 Fig. 3, mounted in the same ways, and having a stop 13 to permit upward movement of the slide 10 by the slide 8. A spring 15 (see Fig. 1) tends normally to raise the front 50 slide 10 toward its uppermost position, being connected to an arm 17 bolted at 19 to the front slide 10.

The above mentioned parts may be, and 55 preferably are, as usual in machines of this type and it will suffice to state that when the foot lever 5 is depressed the Horton clutch connects the constantly rotating fly wheel 3 with the shaft 2 which has a crank 12 pinned to the pitman 6, and the latter is reciprocated, the pitman moving the slide 8 up and down. Then a bow spring 14 entering 60 the path of a shoulder 16 on the Horton clutch 4 throws the latter off and permits the fly wheel to be rotated freely by power.

65 A brake 18 operated by a spring 20 against

an eccentric 22 checks the shaft 2 and crank 12 with the pitman 6 and rear slide 8 at their high point, all this being as usual, and springs 24 and 26 serve respectively to hold the foot lever 5 and clutch controlling member 28 in their normal inoperative positions 70 illustrated in Fig. 1. Other well-known parts include the support 30 for the shoe comprising a swinging post mounted pivotally on the frame 1 at 32, and carrying an 75 adjustable extension rod 34, provided with hand wheel 36, toe support 38 and heel post 40.

In accordance with my invention, as applied to this machine, I provide a plurality 80 of operating devices 42, 44 and 46, which may be heel breasting knives mounted upon a movable supporting member constructed and arranged suitably to permit any one of these knives to be presented in position to 85 breast the heel of a shoe mounted on the toe and heel supporting members 38 and 40 of the jack.

As one convenient form of device to accomplish the above presentation, a turret 90 48 is shown mounted rotatably about a horizontal stud 50 formed upon the front slide 10, a cap plate 52 fastened by screws 54 serving to prevent axial displacement of the 95 turret, which is shown as triangular in front elevation as there are three knives 42, 44 and 46.

In Fig. 1 the knife 42 is shown in its vertical operative position, and a description 100 of its mode of support by the turret will suffice to convey a proper understanding of how each of the knives is supported, the supporting means being preferably of identical construction so that the knives will be 105 interchangeable. The shank 43 of the knife 42 extends upward between bridge blocks 56, 58, and set screws 60 pass through each front bridge block into engagement with the knife shanks and serve to clamp the latter and prevent lateral displacement of the knives. 110 By loosening the screws 60 engaged with either of the knives 42, 44 or 46, the knife may be adjusted relatively to the turret, and when the knife is worn and ground away so 115 that it is desirable to set the bridge blocks 56 and 58 nearer the working edge of the knife a firm grip may still be retained on the shank. The bridge blocks are movably mounted in throat pieces 62, forming part 120 of the structure of the turret 48.

Suitable means may be provided to hold the knives to their work, such as the abutment screws 64 secured against rotation by set screws 66, supported in a portion 68 of the turret which lies between the portions 125 70, 72, Fig. 2. The face 72 is shown as provided with three apertured lugs 74, each fitted to receive an indexing bolt 76 when in registry therewith, to hold the turret steady with one of the knives in operative 130

position, as for example, the knife 42 shown in Fig. 1. This bolt 76, shown clearly in Fig. 2, is carried by a lug 78 on the head of the front slide 10 and is provided with an operating handle 80.

In Fig. 2 may be seen also at 82 one of the detector and shipper devices utilized in this type of machine to engage the shank of the shoe and trip the connection between the 10 knife or front slide 10 and the actuating or rear slide 8. Three of these devices are provided, one for each knife, and I have devised a novel arrangement by which these 15 detectors coöperate interchangeably with the shipper mechanism, being moved automatically by rotation of the turret into place for such coöperation. The construction of these detectors may correspond with that of the well-known type and as illustrated 20 each comprises a two-arm lever 84, 86 mounted on a rock-shaft 88 having bearing lugs 90 on the turret 48. The lever arm 84 carries the detector member proper 82 which is manually adjustable by means of the worm 92 into position to touch the shank of the shoe in the descent of the turret 48, while the other arm 86 of the lever is presented in position to push rearwardly a strut 25 94 mounted pivotally at 96 upon the front slide 10, and having a heel 98 engaged with a spring 100 which normally tends to throw the heel 98 outward and thereby to hold in the position shown in Fig. 2 the strut proper 30 94, whose function is to afford means by 35 which the rear slide 8 is connected at times with the front slide 10 to operate the slide carrying the turret 48 and the knives, such actuation being effected by engagement of the strut 94 with a roller 106 pivoted in the 40 rear slide 8. This roller permits the strut to be pushed out easily, even when under considerable pressure by reason of the downward thrust of the slide 8 under the action of the pitman 6, and those skilled in the art 45 will understand readily that this unshipping action supervenes when the detector 82 strikes the shank of the shoe as the knife 42 reaches the end of the breasting stroke, the detector rotating upon the shaft 88, 50 pushing the strut 94 outward to clear the roller 106, and permitting the slide 10 with turret 48 and knives 44, 44 and 46 to stop in their downward movement and to be subsequently lifted to normal inoperative position 55 by action of the spring 15, in conjunction with the lifting action of the rear slide as it comes in contact with the plate 13 upon its return stroke.

In accordance with my invention I prefer 60 to interpose an independent connecting member 108, such as the push pin illustrated in Fig. 2, between the lever finger 86 and the strut 94, in order to permit freer adjustment of the two part detector lever 84, 86, 65 suitable means being provided for such ad-

justments, as for example by providing a set screw 83, with lock nut 85, carried by the lever 84 as shown in Fig. 2, the point of the screw bearing against a shoulder 89 of the lug 90, so that the lever arm 84 is 70 held normally in the rotative position shown in Fig. 2, even when the rotation of the turret moves the finger 86 away from its position of coöperation with the push pin 108.

In accordance with another valuable feature of my invention, I provide a series of clamping and guiding devices, one corresponding to each of the operating devices in order that the workman may have an accurate guide to assist him in placing the heel 80 of the shoe for treatment, and clamping the same in position and each of these abutment guides may take the form of such a plate as is usually provided in machines of this character, and the operation of which is well 85 understood by those skilled in the art. In the drawings I have shown three of these presser guide plates, 110, 112 and 114, of which the plate 110 is in position for use 90 relatively to the knife 42, and has a contour 95 corresponding with that of the knife, their coöperation being sufficiently clear when it is stated that the shoe having been placed heel upward upon the pin 40 the top of the heel is engaged with the plate 110 and located relatively thereto so that the guiding edge of the plate will be exactly in the position where it is desired that the breasting cut of the knife 42 should take place. I prefer to provide for movement of these 100 abutment guide plates 110, 112, 114 so that each one may be brought readily as needed into the position occupied by the plate 110 for the breasting operation just described. This may be provided for by any suitable 105 structure, and as one convenient form of such device I have shown a turret 116 similar in general arrangement to the turret 48 already described, this turret being supported by a vertical post 118 carried by a 110 bracket 120 pivoted on and extending laterally from a slide 122 mounted to reciprocate vertically in guideways 124 formed in an arm 126 bolted at 128 upon frame 1 of the machine. The slide 122 is connected for actuation with a lever 123 mounted pivotally at 125 upon a bracket 126 on the machine frame and having a pivotal connection 130 with a vertically movable rod 132, preferably of the type usually provided for the 115 actuation of presser guide plates in machines of this character; the slide 122, arm 126, lever 123 and operating rod 132 being preferably of the type well-known to those skilled in the art.

Adjusting means, such as the lock nut 134 (see Fig. 2) and the coil spring 136 with thumb nut 138 to regulate the tension of the spring are usual expedients for the purpose indicated, as is also the thumb nut 140 and 130

clamp 141 to hold the sleeve 142 in place relatively to the lever 123.

The presser guide plates 110, 112 and 114 may be of any suitable material and contour, and may be mounted in any suitable fashion upon the turret 116 and as one convenient construction I have shown plates of the character usually provided in heel breasting machines, but differing from each other in contour, the plates 112 and 114 being reversely curved for treatment of right and left heels of the same pair while the plate 110 exhibits a different curve. The plate 114 also is shown as provided with marking devices 113.

It is desirable to mount each of the plates 110, 112 and 114 for longitudinal adjustment and I have accordingly shown each of the plates as slotted at 117, Fig. 3, to receive 20 each a bolt secured to a back plate 152 and having a wing nut 156, Fig. 2. The forward part of the plate 152 is provided with an undercut groove 154 to receive the head of a stud 150 secured to the back of each of 25 the presser guide plates 110, 112, 114, this arrangement permitting the plates to be moved backward and forward longitudinally in a horizontal plane relatively to the heel post 40 of the shoe support when the wing nuts 30 156 are loosened. Set screws 158 having check nuts 160 are carried by a support 159 formed on the turret 116 and are provided to engage the rearward projection 115 of the back plates 152 respectively to regulate 35 the angular relation of plates 110, 112 and 114 respectively relatively to the horizontal, in order to provide for adjustment to the plane of the top of the heel when the latter departs from the horizontal. For this purpose 40 the back plates may be tilted around horizontal rock shafts 162 passing through the plates into lugs 164 carried by the turret 116. Springs 220 are provided to hold the plate normally in contact with the adjusting 45 screws 158.

Inasmuch as the plates 110, 112 and 114 are usually of such length that the frame 1 would interfere with their swinging movement in a horizontal plane, I have provided 50 for a tilting movement of the entire turret bodily with the plates and for this purpose the bracket 120, to which the turret is pivoted, is pivotally supported by a shaft 168 in a head 170 carried by the vertical slide 122, and as one convenient form of device to 55 operate the turret to tilt the same I have shown a handle rod 172 movable rotatively in a bearing 174 carried by the bracket 120, the forward end of the rod 172 being fluted 60 as at 176 to engage rack teeth formed upon an indexing pin 178 movable vertically in the member 170 to enter each of the series of holes 180 in the turret 116, this pin serving 65 to hold the turret in fixed position with the plate 110 or plate 112 or plate 114 in po-

sition for use as already described. The balance of the turret is such that it remains normally in horizontal position with the upper end of the post 118 against the projection 121 on the slide 122 and is thus held 70 from turning movement when pressure is applied upwardly to the plate which is in operative position. This handle rod 172 may be provided with a coil spring 182 engaged with a pin 184 in the member 170 and 75 a pin 186 in a suitable collar 188 upon the handle rod 172, so that when the handle rod 172 is released the coil spring 182 tends normally to throw the index pin 178 downwardly into engagement with the turret 116. 80

In order to change the position of the plates 110, 112 and 114, the operator grasps the handle rod 172, twists the same around its longitudinal axis to clear the pin 178 from that one of the holes 180 in which it 85 may be placed at the time, and then the operator, still holding the handle 172, uses it to swing the turret 116 bodily with the plates around the shaft 168, and then the turret 116 can be grasped by the operator and 90 turned with the post 118, the plates swinging clear of frame 1 until the selected plate is in practically the position of the plate 110 as shown in the drawings, and then the turret 116 is swung bodily by means of the handle 172 back to its horizontal position, the handle is released, and the operator by moving the plate selected toward its operative 95 position will quickly position it so that the pin 178 will lock it exactly at the position shown in Figs. 1, 2 and 3.

At 194 I have shown a common form of toggle joint between the lever 123 and the vertical slide 122 which carries the turret, the purpose of this toggle joint being to provide for a slight occasional movement of the selected pressed guide plate away from the work, under the control of the operator, independently of the position of the actuating lever 123 and its related parts, permitting 105 the release of the plate from engagement with the shoe so that the shoe can be withdrawn or adjusted to the knife.

Accordingly, in the operation of my improved turret power heel breasting machine, 115 the parts being in the position illustrated in Fig. 1, the shoe is placed upon the last pin 40 and toe rest 38, the hand wheel 36 is turned to operate the extension rod 34 and bring the shoe into approximately its proper 120 position for treatment, adjacent to the guide and abutment plate 110, which is first turned into position as just described, and the turret 48 having been turned about its stud 50 to bring into position the selected knife 42, the 125 latter will be held in place by automatic entry of the index bolt 76 within the proper apertured lug 74. The operator then depresses the treadle 5 in the usual manner, thereby causing plunger 182 to draw down 130

the lever 123 and slide 122, moving the turret 116 downward into its position where the plate 110 engages the heel of the shoe, and further movement of the foot lever 5 throws 5 in the Horton clutch 4 in well-known fashion and the pitman 6 is operated by crank 12 to draw down the rear slide 8 and the front slide 10, through contact of the roll 106 with the strut 94, the front slide 10 carrying with 10 it the knife 42 to breast the heel. At the end of this breasting stroke the detector 82 strikes the shank of the shoe, is rocked on shaft 88 to bring its finger 86 against the push pin 108 to force the strut 94 from under 15 the roll 106 and thus release the knife, slide 10 and operating turret 48 from the actuating slide 8, permitting them to stop their downward movement and await the upward movement of slide 8, which upon coming in 20 contact with the plate or stop 13 raises the slide 10 aided by spring 15. The turret 116 also is raised by the upward movement of plunger 132 under the action of spring 24 when treadle 5 is released, and the apparatus 25 is now ready for another operation which may be a repetition of that already described or any of the operating devices and coöperating presser guide plates may be brought into play by manipulation of their 30 respective turrets in the manner hereinbefore described.

Having described my invention what I claim as new and desire to secure by Letters Patent of the United States is:—

25 1. In a machine of the class described mechanism for performing upon shoes operations analogous to and including the breasting of heels, said mechanism comprising a plurality of turrets rotatable relatively to the work and arranged to present a plurality of operating devices *seriatim* for treatment of said work, one of said turrets being arranged to receive breasting knives, and another of said turrets being arranged to receive presser guide plates corresponding to, and to coöperate with, said knives respectively, and means to support said presser guide turret tiltably, to clear the same during said rotative adjusting movements 50 thereof.

55 2. In a machine of the class described a frame, a slide reciprocable therein and having an operating turret, an actuating slide, means to connect said slides operatively at times, and a series of shipping devices, operable respectively in different positions of said turret to control said operating connections between said slides.

60 3. In a machine of the class described a frame, a slide reciprocable therein and having a turret for a plurality of operating devices, an actuating slide, a connecting member movable to connect said slide at times, means tending normally to hold said member in connecting position, and shipping de-

vices on and movable with said turret one for, and operable with, each of said operating devices to throw off said connecting member.

4. In a machine of the class described a frame, a front slide and a rear slide capable of independent relative reciprocation therein, means to actuate said rear slide, a strut pivotally mounted on the rear of said front slide and having a spring acting upon one arm to throw the other arm into actuating engagement with a portion of said rear slide, to connect said slides actuatingly, a push pin carried by said front slide in position to be moved longitudinally to throw off said strut, 75 a turret on said front slide, and a plurality of shipper levers respectively constructed and arranged to be engaged with the work at times in different positions of said turret and when so engaged to engage also with said 80 pin to push the same and throw off said strut.

5. In a machine of the class described, actuating and operating slides and means to couple said slides, a detector and shipper device comprising a detector arm provided with an adjustable detector, a throw-off arm to operate said coupling means, and means to regulate the normal position of said device bodily and to maintain said device in 95 adjusted position.

6. The combination with an operating turret for machines of the class described, having a plurality of bearing lugs, with shoulders, of a plurality of shafts mounted in 100 bearings in said lugs, detector and shipper levers, one for and connected with each of said shafts, said levers comprising respectively a detector arm and a shipper arm, and a set screw carried by said lever to be 105 engaged with said shoulder to determine adjustably the normal rotative position of said lever and shaft.

7. In a machine of the class described, guide mechanism comprising a slide, a turret having a member supported rotatably upon said slide and provided with a work guide, and means to permit tilting movement of said turret relatively to said slide, to clear said guide for rotative adjustment. 115

8. In a machine of the class described, guide mechanism comprising a slide, a turret having a series of work guides and supported rotatably upon said slide in a plane perpendicular thereto, and means to permit 120 tilting movement of said turret relatively to said plane, said means comprising a horizontal shaft carried by said slide and upon which said turret is mounted.

9. In a machine of the class described, 125 guide mechanism comprising a slide, a turret having a member supported rotatably upon said slide, and means to permit tilting movement of said turret relatively to said slide, said means comprising a horizontal 130

shaft carried by said slide and upon which said turret is mounted, a lock pin, and a twisting handle to be engaged with said pin and provided with a torsional spring tending normally to seat said pin within one of a series of indexing holes in said turret, to determine the rotative position thereof, said handle being movable to retract said pin and to impart tilting movement to said turret bodily.

10. A turret for machines of the class described comprising a body portion having seat parts for a plurality of presser guide plates, said seats being tiltable relatively to the plane of said body portion, and having means respectively to permit longitudinal adjustment of each plate in its seat.

11. In a machine of the class described an operating device turret, a presser guide turret, a foot lever, operating connections between said lever and turrets respectively, for the power actuation of the former turret and manual operation of the latter turret, and means to permit adjustment of said turrets relatively to each other, to effect various combinations of said operating devices and presser guides.

12. A heel breasting machine comprising a knife, means to actuate the same, a presser slide, and a turret provided with a series of presser plates and mounted on said slide for rotation about axes at right angles to each other whereby said turret may be swung about one axis into a position free from the machine to permit the turret to be turned about the other axis to bring the presser plates alternatively into operative position.

13. In a heel breasting machine an actuating slide carrying a roll, a knife slide, a

strut pivoted to the knife slide and normally held with one end beneath the roll, a bell-crank lever carried by the knife slide, an operative connection between one arm of said lever and the strut, and means carried by the other arm of the lever to contact with the shank of the shoe.

14. In a heel breasting machine an actuating slide carrying a roll, a knife slide, a strut pivoted to the knife slide, means for normally holding the strut beneath the roll, sliding means mounted in the knife slide and contacting with said strut, and a lever carried by the knife slide and having an arm in contact with said sliding means and the other arm adapted to be brought into contact with a shoe when the knife has finished its stroke whereby the sliding means is actuated to force the strut from beneath the roll and the movement of the knife slide is arrested.

15. In a heel breasting machine, a breeding device, a shoe-support, and a turret provided with a series of heel presser-plates respectively pivoted between their ends on said turret, resilient means for depressing the rear portions of the plates, and positive adjusting means acting in opposition to said resilient means for adjusting and maintaining the plates in adjusted angular relation to the breeding device.

In testimony whereof I have signed my name to this specification in the presence of two subscribing witnesses.

Corrections in Letters Patent No. 1,133,584.

It is hereby certified that in Letters Patent No. 1,133,584, granted March 30, 1915, upon the application of Ralph C. Simmons, of Beverly, Massachusetts, for an improvement in "Heel-Breasting Machines," errors appear in the printed specification requiring correction as follows: Page 3, line 52, for the reference-numeral "44," first occurrence, read *42*; page 4, line 107, for the word "pressed" read *presser*; page 5, line 63, claim 3, for the word "slide" read *slides*; page 6, line 24, claim 11, for the word "adjustment" read *adjustments*; and that the said Letters Patent should be read with these corrections therein that the same may conform to the record of the case in the Patent Office.

Signed and sealed this 28th day of September, A. D., 1915.

[SEAL.]

J. T. NEWTON,

Acting Commissioner of Patents.
